SEAT CONSTRUCTION

Erwin R. Fensin, Chicago, Ill.

Application March 28, 1936, Serial No. 71,358

5 Claims. (Cl. 155—86)

The present invention relates to seats and is directed particularly to the type known as theatre seats and is further directed to novel constructions of the side supporting brackets or standards in combination with quickly mountable and demountable hinge elements for hingedly mounting a seat for tilting movement, and in combination with quickly mountable or demountable connecting plates for anchoring and holding the seat back in the desired inclined position with respect to the tiltable seat.

In the installation of theatre seats it is frequently found necessary to place the rows of a series of seats in curved relation to the building walls or to the stage, or upon an inclined floor, where each successive or next adjacent seat is slightly lower than the adjacent one, or in a number of irregular positions, because of obstructions, curvatures, inclines of the floors, walls or obstructions in locations wherein the respective seats will bear various non-uniform positions with respect to the adjacent seats in the same row or in the adjacent rows. Such requirements require a seat construction which is flexible and which will not distort or "spring" the seat out of its natural shape, which action usually renders the tiltable seat wholly or partially inoperative and frequently results in quick disrepair, breakage and discomfort to the user.

It is an important object of my invention to wholly overcome the above mentioned objectionable features of seats heretofore known by providing a theatre seat construction wherein a plurality of uniform metal supporting standards having lower integral legs may be secured on a floor in spaced apart relation to accord with any irregular manner in which the row of seats is desired and thereafter permitting quick and convenient mounting of the cushioned seats and pivotally connecting attachable hinge brackets and seat backs to said standards, there being, where desirable, only one supporting standard between two adjacent seats.

A further object of my invention is the provision of a supporting standard for theatre seats and the like made of a single integral metal unit having a plurality of vertically disposed integrally formed apertured lugs or bosses wherein the respective apertures are in vertical alignment with each other in order to receive a single pintle whereby to pivot an upper wing shaped connecting plate for anchoring the seat back and to pivotally mount a metal hinge bracket to which one side of the seat proper is secured.

55 A further object of my invention is the pro-

vision of a seat construction wherein a single supporting standard has formed thereon, integral therewith and on opposite sides thereof, bosses or lugs having apertures in vertical alignment to provide for hinged or pivotal attachment thereto of an upper plate or connecting member, the opposite edge of which is secured to the seat back, and to provide therebelow for pivotal mounting of a hinge bracket which is attached to the side edge of the seat proper, said construction permitting adjacent seats to be satisfactorily secured in position in any one of a number of irregular non-uniform adjacent positions.

A further object of my invention is the provision of a seat construction wherein a hinge bracket, two of which are secured on opposite sides of the seat proper, are mounted to pivot horizontally upon a quickly insertable substantially vertical pintle, the pintle passing through suitable apertured lugs or bosses formed on the supporting standard.

Other and further objects of my invention will be apparent from the following description and claims.

This invention (in a preferred form) is illustrated in the drawings and hereinafter more fully described.

On the drawings:

Fig. 1 is a side elevational view of a theatre seat showing on the forward side thereof the pivotally mounted winging or connecting plate for the seat back and showing the supporting hinge bracket mounted by a single pintle.

Fig. 2 is a cross sectional view taken on the line 2—2 of Fig. 1.

Fig. 3 is a side elevational view of the seat supporting standard itself showing only the vertically aligned apertured lugs and without the back supporting plate or seat supporting hinge bracket.

Fig. 4 is a partially top plan and partially cross sectional view of a theatre seat with adjacent spaced apart standards, the cross sectional portion being taken on line 4—4 of Fig. 2.

Fig. 5 is an enlarged cross sectional view taken on line 5—5 of Fig. 2.

Fig. 6 is a perspective view of the wing or connecting plate whereby the seat back is releasably mounted with respect to the seat standard.

Referring to the drawings, the reference numeral 10 indicates a substantially rectangular metal supporting standard which is preferably cast in one piece and having integrally formed legs 11 and 12 which preferably have their apertured flanged lower ends formed to permit the standard to be secured to the floor or other base.

by means of suitable screws 13, as indicated in Fig. 1. It will be noted that the standard 10 may be of relatively light construction and preferably formed with relatively large apertures 14 and 15 as shown. Integral headed studs 16 are preferably formed in the upper inclined edge of the standard 10 to provide for quick and convenient mounting of an arm rest 17 which is made of suitable material, preferably of wood.

As clearly indicated in Figs. 2 and 3, an integral lug 18 having a vertical aperture therethrough is formed substantially adjacent the upper edge of the standard 10. A lug 19, substantially similar to lug 18, is formed integrally with the rear edge of the standard 10 and at a point substantially mid-way between the ends thereof, and in vertical alignment with the aperture of lug 18. A lug 20 similar to lugs 18 and 19 is formed in alignment with and below and spaced apart from lug 19, as clearly shown in Figs. 1 and 3, the space between integral lugs 19 and 20 being sufficient to provide for the insertion of the apertured portion 21a of a hinge bracket 21. A connecting and anchoring plate 22, preferably of trapezoidal shape shown clearly in Fig. 6, has one edge thereof rolled to form a knuckle 22a and has its opposite longitudinal edge bent at an angle and apertured to provide for the convenient insertion of screws or the like when the same is attached to the back rest or seat back. The hinge bracket 21 forms part of the seat supporting hinge or hinge assembly. Numeral 21a designates an apertured portion of hinge bracket 21. The opposite end of said hinge bracket 21 is pivotally connected to seat arm or hinge arm 24a by suitable pivot 23, as clearly shown in the drawings. As shown in enlarged Fig. 5, the pivotally movable seat or hinge arm 24a has a suitable integral angular apertured flange 24 upon which the longitudinal lower edge of the cushion seat proper rests, as shown also in dotted lines in Fig. 4. Said seat or hinge arms 24a are secured to the seat 27 by suitable screws passing through said angular flanges 24, as shown in Figs. 4 and 5.

It will be noted particularly from Figs. 2 and 5, that each of the supporting frames or standards 10 have integral lugs 18, 19 and 20 on each of the opposite sides thereof and directly opposite to each other. Obviously, one supporting standard 10 serves as a support for the adjacent sides of two adjacent seats, there being two hinge brackets 21 pivoted on opposite sides of the standard as clearly shown in Figs. 2 and 5. Likewise, two connecting plates 22 are pivoted in corresponding relative position on opposite sides of each standard, one thereof having its opposite angular end secured by screws or the like to the side edge of the seat back 25, as clearly shown in Figs. 1 and 4, and the connecting plate 22 on the opposite side of standard 10 being correspondingly secured to the seat back (not shown) of the adjacent seat.

The highly important and novel feature of my invention is the afore-described construction which has the great and novel advantage of permitting a row of standards 10 to be bolted to the floor in spaced apart position, of a distance apart to conveniently permit the mounting of the respective cushion seats 27 therebetween and their attached hinge brackets afore-described. The row of such standards may be curved to accord to any desired curvature of the row of seats. After said standards are positioned, each of the seat backs 25 with its two opposite attached connecting plates 22 are slipped into position so that the

apertured knuckle 22a is in alignment with the apertures of respective bosses 18, 19 and 20. Thereupon the cushion seats of attached hinge brackets are quickly and easily inserted so that the apertured end of the arm 21a will also be in alignment with the respective apertures of lugs 18, 19 and 20, whereupon a pin or pintle 26 is manually inserted to secure and mount the seat backs, cushion seats and connected hinge brackets in position. When it is desired to dismount the theatre seats it is only necessary to remove the respective pintles 26, thence the seats and backs 25. Because of the fact that both the connections between the seat backs 25 and the standard 10 in each case are pivotal and that the connection between the seat supporting hinge brackets 21 is also pivotal, there is no distortion or springing of any of the parts of the seat, and particularly there is no distortion of hinge and pivot 23 and between the arms 22 and 21a of the hinge bracket which is the objectionable feature of seats heretofore known where the seats are required to be placed in irregular positions relative to each other.

I am aware that numerous details of construction may be varied through a wide range without departing from the principles of this invention, and I therefore do not desire to limit the patent granted hereon otherwise than necessitated by the prior art.

I claim as my invention:

1. In a theatre seat having a pivotal seat and a back rest comprising a pair of spaced apart standards; a plurality of apertured lugs formed on each of said standards in vertical alignment; a pair of hinge brackets each comprising a horizontally apertured bracket portion having one end thereof removably and pivotally connected to lugs of a respective standard and an arm pivoted for vertical movement on the free end of said bracket portion; a seat mounted on said arms to provide vertical pivoting movement thereof; a pair of back anchoring plates having one edge of each thereof secured to opposite sides of said back rest and having their other forward edges pivotally mounted respectively in certain of the lugs on the respective standards and in vertical alignment with said pivotal connection of the respective bracket portions and a removable pintle in each standard extending through the lugs thereof and through said apertured portion of said hinge bracket and through said connecting plate to pivotally connect each of said hinge brackets and plates to each standard and providing vertical pivotal movement of said seat and attached hinge bracket arms.

2. In a theatre seat having a pair of spaced apart side supporting standards, a pivotal seat and inclined back rest including a plurality of vertically aligned apertured lugs formed on each of said standards; a hinge bracket comprising an apertured bracket portion pivoted for horizontal movement on each standard in certain of said lugs and an arm pivoted on the free end of said bracket portion for vertical movement; said seat being mounted on a pair of said arms for pivotal vertical movement; a pair of back connecting plates, each said plate having one edge secured on the seat back and its other edge pivotally connected to others of said lugs of the adjacent standard; and a removable pintle in each standard extending through the lugs thereof and through said hinge bracket and through said connecting plate to pivotally mount each of said

hinge brackets and each of said plates to said standards respectively.

3. In a theatre seat having a vertically tiltable seat and an inclined back comprising a supporting standard having a pair of spaced apart legs; a hinge bracket including an apertured portion pivoted for horizontal movement with respect to said standard and an arm pivoted to the free end of said bracket to provide vertical movement thereof; a plurality of spaced apart apertured lugs on said standard certain of said lugs providing for pivotal mounting of said hinge bracket and a connecting plate having one periphery thereof apertured and removably mounted between others of said lugs in alignment with the pivotal connection of said hinge bracket and permitting horizontal pivotal movement of said plate; said plate having its opposite edge connected to the seat back; and a pintle removably mounted in said lugs and extending through said plate and through the apertured portion of said hinge bracket.

4. In a theater seat construction, a metal frame-like standard having a plurality of spaced apart integral vertically aligned apertured lugs thereon, hinge means comprising a hinge bracket and a hinge arm pivoted on said hinge bracket, said hinge bracket being pivoted on said standard for horizontal movement; said hinge arm being

adapted to be connected to a seat, a back anchoring plate having a knuckle along one edge and pivoted therealong to said standard, and a removable pintle in the apertures of said lugs, in said portion of said hinge bracket and in said anchoring plate knuckle whereby said hinge assembly and anchoring plate may be quickly assembled and disassembled. 5

5. In a seat, a pair of spaced apart supporting standards having apertured lugs thereon, a seat member pivotally disposed for vertical movement between said standards, a back rest disposed between said standards, hinge means on each of said standards comprising a hinge bracket pivoted at one end on said standard and an arm pivoted on the free end of said hinge bracket, an anchoring plate pivoted at one edge thereof to each standard and connected at its opposite edge to one edge of said back rest, the pivotal connections of each hinge bracket being in substantial alignment with the pivotal connection of adjacent anchoring plate, and a removable pintle passing through the hinge bracket, adjacent anchoring plate and the apertured lugs on each of said standards, said removable pintle permitting 25 quick mounting and dismounting of said hinge assembly, said seat member and said back rest.
